P. J. CHRISTENSEN

SMILING DOLL

Original Filed June 3, 1925

Inventor:
Peder Jensen Christensen
By *June Daniels* Attorney

Patented Feb. 22, 1927.

UNITED STATES PATENT OFFICE.

PEDER JENSEN CHRISTENSEN, OF ELLIDSHØJ, DENMARK.

SMILING DOLL.

Application filed June 3, 1925, Serial No. 34,670, and in Denmark November 20, 1924. Renewed August 18, 1926.

The invention in question relates to a smiling doll having the advantage compared with dolls known hitherto that, by a pressure on the body of the doll, the face can be distorted in such a way that it will look as if the doll were smiling. Owing to the particular construction of the doll the force acting on the face can be caused to bear upon different positions of the face, so that the smile will conform thoroughly with the appearance of the face.

In the accompanying drawing:

Figs. 1-3 show various stages in the production of a doll according to the invention, 15 Fig. 4 is a horizontal section on the line *a—a* in Fig. 3,

1 is an india-rubber container, which can be pumped full of air until a suitable pressure is reached, and 2 is a wrapper of linen 20 or another material, which can limit the expansion of the rubber-container 1. The wrapper 2 has on the sides of the head two openings 3, Fig. 1, through which the container can be pressed outward. Around the 25 head is laid an elastic band 4, Figs. 2-3; such as to cover the holes 3 in the wrapper 2. This band serves the purpose of limiting and regulating the expansion of the container 1 through the holes 3. By pressing on the 30 body of the doll the air will be driven up into its head and tend to expand it. This expansion, however, cannot take place in the portions directly covered by the wrapper 2; consequently the whole expansion will 35 take place through the holes 3, causing a great sidewise or lateral expansion of the head. This movement is used to produce smiles.

In order to transfer such movement to 40 the face of the doll, which is here shown as printed or otherwise indicated on an extensible mask 5 applied to the head of the doll, Figs. 3-4, a band 6, Figs. 2-4, is placed around the head so as to overlie the elastic 45 band 4. The band 6 is fastened at the back of the head, but is otherwise loose. The ends of the band 6 are fastened inside the mask 5 at the corners of the mouth. By pressure 50 on the body of the doll its head will undergo a sidewise or lateral expansion, which will cause the band 6 to be straightened, and its ends to pull on the corners of the mouth, by which the mouth will be lengthened and the cheeks folded as by a naturally smiling 55 face.

I claim as my invention:

1. A doll, comprising an expansible non-metallic head; an extensible face mask overlying said head; and an inextensible connecting member between the head and the mask 60 to transmit the expansion of the former to the latter to exert a tractive stretching action on the same and thereby change the expression of the mask.

2. A doll, comprising an expansible head; 65 an extensible face mask overlying the head; and an inextensible band connected at its ends to the sides of the mask, and intermediate its ends to the head, to transmit the expansion of the head to the mask to change 70 the expression thereof.

3. A doll, comprising an expansible non-metallic head; a face mask overlying said head and embodying an extensible mouth portion; and means for transmitting the 75 expansion movement of the head to said extensible mouth portion to exert a tractive stretching action on the same and thereby change the expression of the mask.

4. A doll, according to claim 3, in which 80 the transmitting means consists of a band which is connected at its ends to the corners of the mouth and intermediate its ends to the head.

5. A doll, according to claim 3, in which 85 the transmitting means consists of a band which passes around the head and is connected at its center to the back of said head and at its ends to the corners of the mouth.

6. A doll, comprising an expansible non- 90 metallic head; a face mask overlying the head and having an extensible mouth portion; and means for exerting an outward pull in opposite directions upon the corners of said mouth portion when the head is expanded, to stretch the mouth and thereby 95 change the expression of the mask.

7. A doll, comprising an expansible head; 100 an inextensible covering enclosing the same but having openings through which the underlying exposed portions of the head are caused to project when the head is expanded; an extensible face mask overlying the front part of said covering; and means for transmitting the projecting movement of said exposed portions to said mask to stretch the same and thereby change its expression.

8. A doll, comprising an expansible head; 110 an inextensible covering enclosing the same but having openings through which the un-

derlying exposed portions of the head are caused to project when the head is expanded; a face mask overlying the front part of said covering and embodying an extensible mouth portion; and means for transmitting the projecting movement of said exposed portions to said mouth portion to stretch the same and thereby change the expression of the mask.

9. A doll, comprising an expansible head; an inextensible covering enclosing the same but having openings through which the underlying exposed portions of the head are caused to project when the head is expanded; an extensible face mask overlying the front part of said covering; and a band encircling said head and connected to said mask, said band overlying the exposed portions of the head so as to transmit their projecting movement to the mouth portion to stretch the same and thereby change its expression.

10. A doll, comprising an expansible head; an inextensible covering enclosing the same but having openings through which the underlying exposed portions of the head are caused to project when the head is expanded; a face mask overlying the front part of said covering and embodying an extensible mouth portion; and a band encircling said head and connected at its ends to the corners of said mouth portion, said band overlying the exposed portions of the head so as to transmit their projecting movement to the mouth portion to stretch the same and thereby change its expression.

In testimony whereof I affix my signature.
PEDER JENSEN CHRISTENSEN.
